CUTTERHEAD FOR HAIR CLIPPERS

Ellis M. Brown and Ernest Harry Forss, Racine, Wis., assignors to John Oster Manufacturing Company, Racine, Wis., a corporation of Wisconsin

Application January 31, 1949, Serial No. 73,831

4 Claims. (Cl. 30—223)

1

This invention relates to hair clippers and refers particularly to the cutter head thereof.

Practically all hair clippers now in use, whether hand operated or power driven, employ a cutter head consisting of complementary upper and lower blades, the front edges of which are toothed to effect a shearing action as the movable blade is shifted laterally across the stationary blade.

Obviously the blades must be held together under tension to enable proper shearing action, and in the past many different ways have been employed to obtain this necessary tension. Where the tensioning means employs adjusting screws or the like the user of the clipper often disturbs the proper setting of the tension with the result that the clipper does not perform satisfactorily.

It is, therefore, an object of the present invention to provide a cutter head for hair clippers wherein the tensioning means is so constructed as to afford fairly reliable assurance against meddling with the factory set tension.

In most cutter heads heretofore in use the blades have a crosshead-like interengagement constraining the movable blade to linear reciprocation, and the tensioning means merely holds the movable blade on its tracks so to speak.

With a view toward eliminating the obvious expense of machining the tracks and guideways forming the crosshead, it is another object of this invention to provide a cutter head wherein the tensioning means not only holds the blades together under proper tension but also serves as the sole support for the movable blade and in itself holds the same in proper relationship to the stationary blade.

The manner of driving the movable blade in cutter heads heretofore in use generally consisted of a socket formed in the blade and a rocking lever having an end portion thereof received in the socket. This construction becomes noisy in use due to the increasing clearance between the parts resulting from the inevitable wear. To overcome this disadvantage the present invention has as another of its objects to provide an improved manner of drivingly connecting the movable blade with the power driven actuator.

In this connection it is a further object of this invention to so construct the tensioning means that it performs this additional function of transmitting motion from the actuator to the blade.

Finally it is the purpose of this invention to reduce the cost of manufacturing the cutter heads of hair clippers.

With the above and other objects in view which will appear as the description proceeds, this in-

vention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates one complete example of the physical embodiment of the invention constructed in accordance with the best mode so far devised for the practical application of the principles thereof, and in which:

Figure 1 is a side view of an electric hair clipper having the cutter head of this invention applied thereto, parts thereof being broken away and in section;

Figure 2 is a perspective view of the cutter head and the front end portion of the clipper; and

Figure 3 is a side view of the combination blade tensioning and driving unit.

Referring now particularly to the accompanying drawing in which like numerals designate like parts throughout the several views, the numeral 5 designates generally an electric hair clipper which may be of the type forming the subject matter of the copending application, Serial No. 73,832, filed January 31, 1949.

As described in detail in said application the clipper includes an outer housing 6 of a size to be conveniently held in the hand, an electric motor (not shown) drivingly connected with an actuator in the form of an eccentric 7. The drivng connection between the motor and the eccentric includes suitable transmission gearing (not shown) housed within a gear case 8.

The front end of the housing 6 slants upwardly and is partially closed by a wall 9 to which a cutter head indicated generally by the numeral 10 is removably secured by screws 11. The cutter head 10 comprises a stationary lower blade 12 and a movable upper blade 13 arranged in superimposed relation with the upper movable blade adapted to move freely across the top of the stationary blade.

As is customary, the complementary blades have cutting teeth 14 along the front edge thereof of which effect the desired shearing action during sidewise reciprocation of the movable blade.

As distinguished from past constructions there is no crosshead constraining the movable blade to linear motion. Instead the adjacent faces of the two blades have narrow flat ground surfaces 15 and 16 in sliding superimposition so that the movable blade is free to move in all directions.

with respect to the stationary blade. The elimination of the crosshead or interengaging trackways heretofore used to constrain the movable blade to linear reciprocation obviously effects a reduction in the cost of manufacture since all finishing of the meeting surfaces involves merely a surface grinding operation which also sharpens the blades.

The blades are held together under tension by means of a novel spring yoke 17, anchored to the stationary blade 12 and overlying and bearing down on the movable blade 13. This yoke is formed of spring steel and is substantially U-shaped with its closed end 18 flat and secured to an upstanding tongue 19 on an attaching bracket 20, the bracket 20 being fastened to the back of the stationary blade by screws 21.

The free ends of the arms 22 of the yoke are detachably secured to the movable blade by pins 23 fastened to laterally extending ears 24 on the arms 22 and received in holes 25 in the movable blade.

As best shown in Figure 3 the tongue 19 of the mounting bracket 20 forms a slightly acute angle to the plane of that portion of the bracket fastened to the back of the stationary blade. Hence, the arms 22 of the spring yoke are directed downwardly to bear down on the movable blade with a spring tension depending upon the angle to which the tongue 19 is bent.

The bracket 20 with its integral tongue 19 is made of semi-hard steel so that it normally resists deformation but can be bent at the factory to obtain proper spring tension, and as will be readily apparent, since this manner of adjusting the blade tension involves no screws or the like it affords fairly reliable assurance against the user of the clipper meddling with the spring tension and thereby interfering with proper functioning of the cutter head. Also, since the cutter head is an assembly complete in itself and independent from the clipper, replacement and interchangeability of cutter heads is facilitated.

In the application of the cutter head to the clipper, the inner anchored end of the spring yoke is received in a cutout 26 in the front wall 9 of the clipper housing, and the eccentric 7 snugly enters the space between the outer ends of the spring arms. To provide increased bearing surfaces between the arms and the eccentric the width of the arms is increased by rearward extensions 27 on the free ends of the arms. Thus as the eccentric revolves the arms of the spring yoke are flexed back and forth to swing the movable cutter blade 13 in a wide arc. Hence, the two spring arms of the yoke are pivoted at their outer ends to the movable cutter blade, the mounting of the blade forms substantially a parallelogram so that the cutting edges of the blades are always parallel, and as the arc through which the movable blade is swung is very nearly flat, for all practical purposes the motion of the blade 13 may be characterized as reciprocation.

From the foregoing description taken in connection with the accompanying drawing, it will be readily apparent to those skilled in the art that this invention provides a cutter head for hair clippers which possesses many advantages over those heretofore available, particularly as to the cost of manufacture and freedom from meddling adjustment of blade tension by unskilled persons.

What we claim as our invention is:

1. A cutter head for hair clippers, comprising: a stationary blade having a back edge and a toothed front edge; a movable blade superim-

posed upon the stationary blade and having cutter teeth on its front edge coacting with the teeth of the stationary blade; a U-shaped spring yoke having substantially parallel blade-like arms flatwise opposing one another and relatively close together, said blade-like arms having a length slightly less than the distance between the front and back edges of the stationary blade, and the free end portions of the blade-like arms providing spaced opposed driving abutments to receive a rotatable driving eccentric therebetween; flanges on the free ends of the blade-like arms extending from the outer sides of the arms adjacent to one edge thereof and lying in a common plane normal to the flatwise planes of the blade-like arms; a connection between the spring yoke and the stationary blade mounting the yoke on the cutter head with the bight of the U spaced from but directly over and substantially aligned with the back edge of the stationary blade and the arms of the spring yoke projecting toward the cutting edge of the head, and with the flanges on the arms pressed flatwise down upon the movable blade to hold the blades together under tension, said connection including resilient means on the bight of the U-shaped spring yoke projecting toward the free ends of the blade-like arms in spaced relation to the edges having the flanges extending therefrom and secured to the stationary blade; and means drivingly connecting the flanges on the free ends of the blade-like arms with the movable blade so that rotary motion of an eccentric engaged between said driving abutments may be yieldably translated into reciprocatory movement of the movable blade through the resilient blade-like arms of the spring yoke.

2. The cutter head set forth in claim 1 further characterized by the fact that the resilient means mounting the U-shaped spring yoke on the stationary blade comprises a bracket having a base flatwise secured to the stationary blade and an upstanding tongue attached to the bight of the U, said base and upstanding tongue being disposed at a slightly acute angle to one another with said angle determining blade tension so that by varying the angle prior to attachment of the yoke to the cutter head, the blade tension may be adjusted.

3. A cutter head for hair clippers, comprising: a stationary lower blade having a back edge and a toothed front edge; a movable blade superimposed upon the stationary blade and having cutter teeth on its front edge coacting with the teeth of the lower blade; a U-shaped spring yoke having substantially parallel blade-like arms flatwise opposing one another and relatively close together, said arms having a length slightly less than the distance between the front and back edges of the stationary lower blade; flanges on the free ends of the blade-like arms extending from the outer sides of the arms adjacent to one side thereof and lying in a common plane normal to the planes of the arms; extensions on the edges of the blade-like arms opposite the flanges and adjacent to the free ends of the arms and coplanar therewith, said extensions cooperating with the free end portions of the arms to provide spaced driving abutments to receive a rotatable driving eccentric therebetween and having thrust receiving surfaces of substantial area engageable by the eccentric; resilient mounting means connected between the bight of the U-shaped spring yoke and the stationary blade to mount the yoke thereon with the bight.

of the U directly over and substantially aligned with the rear edge of the stationary blade and the blade-like arms of the spring yoke projecting toward the cutting edge of the head, and with the flanges on the arms pressed flatwise down upon the movable blade by the resilient mounting means to hold the blades together under tension; and means drivingly connecting the flanges on the free ends of the arms with the movable blade so that rotary motion of an eccentric engaged between said driving abutments may be yieldably translated into reciprocatory movement of the movable blade through the resilient blade-like arms of the spring yoke.

4. A cutter head for hair clippers including a stationary blade having a back edge and a toothed front edge, and a movable blade superimposed upon the upper side of the stationary blade with its back edge intermediate the front and back edges of the stationary blade and having cutter teeth on its front edge coacting with the teeth of the stationary blade; characterized by the provision of a bracket comprising a base portion flatwise secured to the upper side of the stationary blade, and an upstanding tongue resiliently joined to said base portion to be capable of flexure toward and from said base portion, said tongue being substantially in line with and extending upwardly with respect to the back edge of the stationary blade, and said base portion lying wholly between the back edges of the stationary and movable blades; and further characterized by the provision of a U-shaped spring yoke fixed to said tongue with its bight flatwise engaged with the tongue, said yoke having for-

wardly extending substantially parallel blade-like arms flatwise opposing one another and relatively close together, said arms being disposed edgewise to the upper side of the stationary blade and having a length slightly less than the distance between the front and back edges thereof, and said arms having flanges on their forward ends drivingly connected with the movable blade, said flanges extending from the outer sides of the arms adjacent to the lower edges thereof and yieldingly pressed flatwise down upon the movable blade by the tongue to hold the blades together under tension; and extensions on the upper edges of the arms coplanar with the blades and cooperating with the front end portions thereof to provide spaced driving abutments to receive a rotatable driving eccentric therebetween and having thrust receiving surfaces of substantial area engageable by the eccentric.
